UNITED STATES PATENT OFFICE.

ROUSSEAU H. OPES, OF CLEVELAND, OHIO, ASSIGNOR TO THE LAKE SHORE NOVELTY COMPANY, OF CLEVELAND, OHIO, A CORPORATION OF WEST VIRGINIA.

DETONATING DEVICE.

SPECIFICATION forming part of Letters Patent No. 715,130, dated December 2, 1902.

Application filed November 3, 1902. Serial No. 129,990. (No model.)

To all whom it may concern:

Be it known that I, ROUSSEAU H. OPES, a citizen of the United States, and a resident of Cleveland, county of Cuyahoga, and State of 5 Ohio, have invented a new and useful Improvement in Detonating Devices, of which the following is a specification, the principle of the invention being herein explained and the best mode in which I have contemplated 10 applying that principle, so as to distinguish it from other inventions.

My invention relates to detonating devices having a detonating-chamber and a movable plunger operating therein to explode a tor- 15pedo placed in the chamber intermediately of the plunger and chamber-walls.

The object of such invention is to provide a structure which may be economically constructed and embody the requirements nec- 20essary for safety and facility of operation, and particularly to avoid the sticking of the bolt to the detonating-head during the construction or operation of the device.

The annexed drawings and the following de- 25scription set forth in detail certain mechanism embodying the invention, such disclosed means constituting but one of various forms in which the principle of the invention may be used.

30 In the annexed drawings, Figure 1 is a front elevation of the preferred form of the detonating device embodying the principles of my invention. Fig. 2 is a longitudinal sectional view, on an enlarged scale, taken through the 35 center of Fig. 1 and showing the parts in position before exploding a torpedo. Fig. 3 is the same as Fig. 2, but showing the parts in position during the explosion; and Fig. 4 is a modified form of my improved device, show- 40ing a downwardly-tapering bolt.

A, Fig. 1, is the head of my improved de- 45vice, provided with a bore *a* at its upper end, into which may be inserted a cane or staff *b*, by which the device is operated. Cast integral with the sides of the bore *a* and immedi- 50ately below the bore is a conical detonating-bolt *c* of increasing diameter from top to bottom. The bottom of the bolt is cast within an explosion-chamber *B*, the sides of which are 55 slanting and form a conical opening *d* out of

the chamber, which increases in diameter as it approaches the interior. The outer end of the opening *d* is somewhat less in diameter than is the diameter of the bottom of the bolt *c*, so that while the base of the device cannot 55 be shaken loose from the head when the device is being carried, as illustrated in Fig. 2, neither is any part of the head, with the exception of the bottom of the detonating-bolt, in contact with the explosion-chamber during 60 the explosion, as illustrated in Fig. 3. The diameters and lengths of the opening *d* and the bolt *c* are such that a substantial opening between the bolt and the sides of the chamber is left for the escape of gases of 65 explosion when the bolt is pushed into the chamber and occupies its innermost position just prior to explosion. This feature greatly reduces the danger of breaking of the bolt-head by offering a very free avenue of escape to 70 said gases. Through a small opening *e* in the side of the explosion-chamber *B* a torpedo *f*, Fig. 3, may be placed upon the bottom of the same. The detonating-bolt *c* and the explosion-chamber *B* are cast in one operation in 75 the manner well known to those skilled in the art, the bolt being at the time of casting midway within the chamber, so that it is not only not in contact with the latter at any point, but is everywhere separated from it by a con- 80siderable distance, and thus there is no danger of sticking during the casting.

Making the sides of the explosion-chamber parabolic and the detonating-bolt so that it may be driven upward are modified forms of 85 my device, the latter of which is illustrated in Fig. 4; but in all forms the essential feature of the tapering bolt procures the advantages and obviates the difficulties hereinbefore described.

90 Other modes of applying the principle of my invention may be employed instead of the one explained, change being made as regards the mechanism herein disclosed, provided the means stated by the following claim or the 95 equivalent of such stated means be employed.

I therefore particularly point out and distinctly claim as my invention—

In a detonating device, the combination 100 with an integral detonating-head formed with

an explosion - chamber, an opening leading thereto for the introduction of torpedoes, and a second aperture of conical form leading out of such chamber; of a conical bolt seated and movable in said conical aperture but irre-
5 movable therefrom, the diameter and length of the bolt and diameter and length of the aperture being such that a substantial open-

ing for gases of explosion will be formed when the bolt is moved into the chamber.

Signed by me this 1st day of November, 1902.

ROUSSEAU H. OPES.
